UNITED STATES PATENT OFFICE

CHARLES S. CARD, OF DENVER, COLORADO

PARALLEL-THROW SPRING-LOCK SWITCH STAND FOR RAILROADS

Application filed April 3, 1930. Serial No. 441,261.

My invention relates to a parallel throw spring lock switch stand for railroads.

The objects of my invention are:

First, to provide a hand operating spring locking parallel throw switch stand for right or left hand turnouts which will automatically hold the switch points tight against the rail.

Second, to provide a switch stand for throwing the switch points of right or left hand turnouts that is arranged and adapted to be placed on either side of a track parallel with the rails, thus allowing it to be installed in narrow tunnels.

Third, to provide a simple, positively operating structural-steel constructed switch stand of great strength and durability for use especially in the narrow tunnels of coal and ore and other underground mines.

I attain these objects by the mechanism illustrated in the accompanying drawings in which:

Fig. 1 is a plan view of the improved switch stand.

Fig. 2 is a side view thereof.

Fig. 3 is a perspective view of one leg of the switch stand.

Fig. 4 is a sectional view on the line 4—4 of Fig. 2.

Fig. 5 is an end view of the other leg of the switch stand.

Fig. 6 is a plan view of the bell crank which connects the operating lever and the draw bar which is connected to the switch points.

Fig. 7 is an edge view of the same.

Fig. 8 is a sectional view on the line 8—8 of Fig. 9 and

Fig. 9 is a plan view showing a main track and right hand turnout and the manner of connecting the switch points with the improved switch stand.

Referring to the accompanying drawings, the letter A refers to a switch stand which is made up of two members, each of which comprises vertical legs 1 and 2 respectively which are bent over at their upper ends in line with the legs to form horizontal bars 3 and 4 respectively, the major portions of which are slightly offset from the rest of the

bar as shown at 5 and 6. These bars are placed together so that the offset end of one bar rests against the main portion of the other bar, and the two bars are secured together by rivets 7. By this construction, a space X of suitable length is formed between the offset portions of the bars 5 and 6 and of a width corresponding to the thickness of a hand lever to be later described as will be seen by reference to Fig. 3. The lower end of the leg 1 terminates in a right angled foot 8 and the lower end of the leg 2 terminates in a right angled foot 9 which extends in a direction opposite to the foot 8. An angle plate 10 is riveted at its upper end to the leg 1 as shown at 11, the horizontal portion of this plate forming a foot 8A which extends in a direction opposite to the foot 8. The vertical portion of this angle plate below its riveted end is spaced from the leg 1 for a purpose which will presently appear.

An angle plate 12 is riveted to the leg 2 as shown at 13 in Fig. 3 and the horizontal portion of this plate forms a foot 9A which extends in a direction opposite to the foot 9. A horizontal cross bar 14 is connected at one end to the leg 2 by one of the rivets 13 and its opposite end passes between the leg 1 and the angle plate 10 and is secured by a rivet 15 which passes through the angle plate 10, the bar 14 and the leg 1, as clearly shown in Fig. 5. The middle portion of the bar 14 is slightly offset from its end portions as shown at 16 in Figs. 3 and 4 and this offset portion 16 is in direct vertical line with the space X between the offset portions 5 and 6 of the horizontal bars of the switch stand.

The lower end portion of a hand lever 17 is inserted in the space X between the offset members 5 and 6 of the stand and is secured to the members by a pivot bolt 18. The lower end of this lever is provided with a longitudinal slot 19 and a pin 20 passes through this slot and through the upper ends of a pair of secondary levers 21 which are pivotally connected centrally of their lengths to the offset portion 16 of the cross bar 14, the cross bar being between the levers. One end of a link 22 is passed between the lower ends of the secondary levers 21 and is pivotally

connected thereto by a pin 23. The lower ends of a pair of coil springs 24 are hooked upon the opposite ends of the pin 23 and the upper ends of these springs are hooked to 5 eyes on the lower ends of a yoke shaped rod 25 which passes through the hand lever 17 above the point of its pivotal connection with the switch stand. The purpose of these springs will later appear.

10 The switch stand A is secured upon the end portions of a pair of the usual railway cross ties in the manner shown in Fig. 9, the feet 8 and 8A being secured to one tie and the feet 9 and 9A being secured to inwardly projecting portions of base plates 26 which are secured to the adjacent tie, thus leaving an open space between the said projecting portions of the base plates and the road bed as shown in Fig. 2. The feet 9 and 9A are secured to the base plates 26 by bolts 27 and 28, the bolts 28 being of greater diameter than the bolts 27 and washers 28A are welded to the undersides of the plates 26 concentric with the holes through which the bolts 25 28 pass. The bolts 28 are pivot bolts, and in the arrangement shown, the bolt 28 which passes through the foot 9 carries a bell crank 29 comprising duplicate parallel members which are separated by a spacing block 30 at 30 the apex of the crank, the washer 28A serving as a spacer between the bell crank and the under side of the plate 26, as clearly shown in Figures 2 and 8. The link 22 is given a quarter twist as shown in Fig. 2 and its free end is passed between the plates of the adjacent end of the bell crank and is secured thereto by a pivot pin 31. To the opposite end of the bell crank 29 is pivotally connected one end of a link 32, which is preferably 40 made of two superposed metal strips, a space being left between the free ends of the strips to receive one end of a draw bar 33 which is secured to a pair of switch points 34 and 35 of a right hand turnout, as shown in Fig. 9. In 45 this figure, B and C refer to the main track, rails and D and E to the turnout rails. The rear end of the switch point 35, joins the turnout rail D and the rear end of the switch point 34 joins the main track rail C, so that 50 when the points are in the position shown in Fig. 9, the front end of the point 35, engages the main rail B, and the front end of the point 34 is spaced from the main rail C, thus opening the turnout. When the points 55 are in the reverse position, the turnout is closed and the main track is open, this arrangement of the switch points being old and in general use. The draw bar 33 bears 60 against the under sides of the flanges of the rails B and E and extends beyond the rail B so as to have a bearing contact with that rail, when the switch points are thrown to open the main track. The switch points are 65 secured to the draw bar 33 by angle plates 36 which are riveted to the points and to the

bar, and strap irons 37 are riveted to the horizontal portions of the angle plates and to the bar, thus strengthening the connection between the draw bar and the switch points.

By the construction shown and described, the throw of the switch lever 17 is parallel with the direction of the main track instead of at right angles thereto, as in the constructions in present use, thus enabling the improved switch stand to be employed in places such as narrow tunnels, when it would be impossible to use a switch lever having a throw at right angles to the track, without making an opening in the adjacent side of the tunnel wall. When it is necessary to place the switch stand on the opposite side of the track from that shown in Figure 9, the bell crank 29 is removed from the bolt 28 which passes through the foot 9 of the switch stand and is mounted on the corresponding bolt 28, which passes through the opposite foot 9A; the ends of the bell crank are then connected to the link 22 and to the adjacent end of the draw bar in the same manner as shown in Fig. 9.

In operation, the switch points being in the position shown in Fig. 9 or so as to switch from the main track to the turnout, and it is desired to close the turnout and open the main track, the switch lever 17 is thrown in the direction indicated by the arrow in Fig. 2, the secondary levers 21 are thereby swung in the opposite direction and the link 22 which connects these levers with the bell crank 29, turns the said bell crank in the direction of the arrow, as indicated in Fig. 1, whereby the draw bar is pulled upon to shift the switch points to the reverse position, thus closing the turnout and opening the main track. As the levers 17 and 21 swing toward a dead center line, the coil springs 24 are drawn upon or expanded, and as the levers pass the dead center line, the springs contract and not only complete the throw of the levers but lock them in these positions, thus holding the draw bar and parts connected therewith against accidental movement. The springs thus act to automatically lock the levers at the limit of their throw in either direction, thus preventing accidental shifting of the switch points.

The link 32 forms a swinging connection between the bell crank and the draw bar, which permits the draw bar to move in a path defined by the movement of the switch points.

Having described my invention, what I claim as new and desire to secure by Letters Patent, is:—

1. In mechanism of the character described, the combination with a railway track, associated switch points; a draw bar connecting said switch points and a pair of cross ties; of a switch stand having opposite base members; inwardly projecting base plates on one of said ties which support one

base member of said stand and bolts extending through said base members and said base plate, the other base member being secured to the opposite tie; a bell crank 5 mounted on one of said bolts; a link connecting one end of said bell crank and the adjacent end of the draw bar; a hand lever mounted on said stand to swing parallel with the track; an oppositely inclined secondary lever connected at its upper end to the slotted lower end of the hand lever and a link connecting the lower end of the secondary lever and the other end of the bell crank, whereby when the hand lever is swung in 10 either direction, the draw bar is moved at right angles to the throw of the hand lever. 15

2. The combination with a railway track; a pair of associated switch points and a draw bar connecting said switch points; of 20 a switch stand adjacent said track; a hand lever and a secondary lever pivotally mounted on said stand and inclined in opposite directions and parallel with the track, the upper end of the secondary lever having a sliding connection with the lower end of the hand lever, one leg of the switch stand being supported so as to leave a space between the same and the road bed; a bell crank mounted on the under side of said leg; a 25 link connecting one end of said bell crank and the lower end of the secondary lever; a link connecting the other end of the bell crank and the adjacent end of the draw bar, whereby movement of the hand lever effects 30 an opposite movement of the secondary lever, thereby turning the bell crank to shift the switch points.

In testimony whereof, I affix my signature.
CHARLES S. CARD.
